UNITED STATES PATENT OFFICE

105,312

DESIGN FOR GOGGLES

Leonard P. Young, Chester, Conn.

Application June 5, 1937, Serial No. 69,689

Term of patent 14 years

To all whom it may concern:

Be it known that Leonard P. Young, a citizen of the United States and resident of Chester, in the county of Middlesex and State of Connecticut, has invented a new, original, and ornamental Design for Goggles, of which the following is a specification, reference being had to the accompanying drawing forming part thereof, in which

Fig. 1 is a top view of my goggles; and
Fig. 2 is a front elevation thereof.

The design consists of two symmetrically arranged resilient bodies ornamentally curved in the rear and straight-lined at the front ends. These ends of the goggles are oblong in shape so as to ornamenteally offset the curved rear portions of the bodies, in which oblong ends are set rectangular lenses.

I claim:

The ornamental design for goggles as shown and described,

LEONARD P. YOUNG.
